UNITED STATES PATENT OFFICE.

EDWARD W. CLINCHARD, OF SEDRO WOOLLEY, WASHINGTON.

WASHBOARD.

1,139,847.

Specification of Letters Patent.

Patented May 18, 1915.

Application filed December 3, 1913. Serial No. 804,504.

To all whom it may concern:

Be it known that I, EDWARD W. CLINCHARD, a citizen of the United States, residing at Sedro Woolley, in the county of Skagit and State of Washington, have invented new and useful Improvements in Washboards, of which the following is a specification.

This invention relates to wash boards and one of the objects of the invention is to provide a device of this character with a soap receiving receptacle communicating with the rubbing surface of the board so that the requisite amount of suds may be conducted to the clothes in the operation of rubbing them on the board without unduly wearing the soap away.

Another object of the invention is the provision of a device of this character so constructed that the reinforcing parts of the rubbing surface or board are utilized to space the same from the back of the legs, to retain the board in proper position and to form an inclined soap ledge which directs the drippings of the soap thereon to a receptacle having apertures opening onto the rubbing surface of the board.

Further objects of the invention will appear as the following description is read in connection with the accompanying drawing, which forms a part of this application, and in which:—

Figure 1 is a front elevation. Fig. 2 is a vertical sectional view on the line 2—2 of Fig. 1. Fig. 3 is a horizontal sectional view on line 3—3 of Fig. 1. Fig. 4 is a rear view of the rubbing plate showing the inclined top wall and soap holder.

Referring more particularly to the drawing, 1 and 2 represent the supporting legs which are longitudinally grooved at their sides, as shown at 3, to receive the rubbing board 4 and are connected together at their upper and lower ends by a cross piece 5. The rubbing board is constructed preferably of a piece of metal but may be made of any suitable material, such as procelain, glass or the like and is provided at its upper edges

with right angular flanges 6 and 7, the latter being of a width equaling the width of the grooves so as to hold the front of the rubbing surface against the front wall of the groove, as will be readily understood. The former flange 6 is considerably wider than the flange 7 so as to extend from the front wall of the grooves 3 to the rear edge of the ledge and to abut against a back board 8 which extends from the cross piece to a point slightly below the top of the rubbing surface and forms with the flange 6, the cross piece 5 and the legs 1 a receptacle for soap. The flange 6 is notched adjacent its ends, as shown at 9, to permit the rear edge thereof to extend back of the back board and to allow for the offset caused by the groove 3. The flange 6 is also inclined from its outer edge to the center of the upper part so as to direct the drippings from the soap toward the chamber 10 which is constructed by placing a casing 11 on the rear of the rubbing board and forming an opening in the flange 6 to receive the casing. The casing is provided with an inclined bottom 12 and the front of the rubbing board has apertures 13 formed therein to permit ingress of the water into the chamber and the egress of the soap suds therefrom. Suitable, removable securing devices, such as bolts, screws or the like, as indicated at 14, are passed through the legs 1 and 2 and through the lower end of the rubbing board so as to prevent the legs from separating, the rubbing board in this instance serving in the capacity of a bridge piece which is commonly used.

What is claimed is:—

In a wash board, a pair of supporting legs having longitudinal grooves therein, a rubbing board arranged within the grooves between the supporting legs and provided in its central upper portion with apertures, flanges upon the upper and lower edges of said rubbing board for holding the face of the rubbing board against the front wall of said grooves, the upper of said flanges

being extended to the rear edge of the supporting legs to form a supporting ledge and inclined from its opposite ends in a direction toward its center and provided in its 5 horizontal central portion with an opening, a casing open on its face and top having an inclined bottom and closed sides and back secured in the opening in the upper

flange and over the openings in the rubbing board as and for the purpose set forth. 10

In testimony whereof I affix my signature in presence of two witnesses.

EDWARD W. CLINCHARD.
